FASTENING DEVICE

Alexander Charron, Fall River, Mass.

Application April 25, 1932, Serial No. 607,450

1 Claim. (Cl. 20—92)

This invention relates to fastening devices and particularly to a two part fastener of simple construction for use in fastening wood or similar material, for example, as a box-fastener or as a bonding or tying agent in building construction.

It is an object of this invention to provide a fastener which eliminates the necessity of using nails.

A further object is to provide a device which will be of easy appliance to the things it is desired to fasten.

Another object is to provide a fastener which will grip and hold together in a very secure manner the pieces of material it is desired to fasten.

With these and other objects in view, the invention consists in certain novel features of construction and combinations and arrangements of parts as will be more fully hereinafter described 20 and claimed.

My invention is illustrated in the accompanying drawing, forming part of this application, in which

Figure 1 is the male portion of the device,
25 Figure 2 is the female portion of the device.

Figures 3 to 6, inclusive, illustrate the successive stages in the application of the device in the fastening together of two pieces of material.

Referring to the drawing, I have shown therein 30 a fastener comprising a substantially U-shaped male member 10 and a similarly shaped but shorter male member 11.

The male member comprises a base portion 12 and a pair of parallel arms 13 extending therefrom at right angles and having a pair of hooks 14 at their extremities, the points 15 of these hooks being parallel to the arms 13.

The female member comprises a base portion

16 and a pair of parallel arms 17 extending therefrom at right angles, but being of less length than the corresponding arms 13 of the male member, and a pair of hooks 18 at the extremities of the arms 17, the points 19 of these hooks being 60 parallel to the arms 17.

In the operation of the device, the points 19 of the female member 11 are first driven into one piece of material so that the arms 17 lie flat upon the material. The base portion 12 of the male 65 member 10 is then inserted between the arms 17 of the female member 11 and the points 15 are driven into the other piece of material as shown in Figures 3 and 4.

The male member 10 is then bent by any suitable instrument, such as a screw driver 20, as shown in Figure 5, so that it is looped over the female member 11 and then hammered to a position as near the surface of the fastened materials as is practical.

Various slight changes might be made in the general form and arrangement of parts described without departing from the invention, and hence I do not limit myself to the precise details set forth, but consider myself at liberty to make 80 changes and alterations as fairly fall within the spirit and scope of the appended claim.

I claim:

A fastening device comprising a substantially U-shaped member having comparatively short 85 extensions extending at right angles from the legs of the member in parallel relation to each other and from the same side of the member and terminating in return bent spikes parallel to the legs and a similarly constructed relatively longer 90 member adapted to pass through the first member for interengagement therewith.

ALEX. CHARRON.
